UNITED STATES PATENT OFFICE.

MOÏS H. AVRAM, OF NEW YORK, N. Y.

COMPOSITE STOCK-CERTIFICATE.

1,148,946.

Specification of Letters Patent. Patented Aug. 3, 1915.

Application filed January 19, 1915. Serial No. 3,017.

To all whom it may concern:

Be it known that I, Moïs H. AVRAM, a citizen of the United States, residing at New York city, county and State of New York, have invented certain new and useful Improvements in Composite Stock-Certificates, of which the following is a specification.

This invention relates to novel means by which the security offered to the stock holders is increased, business expenses are reduced, and a fund is created out of which any temporary falling off in the earning capacity of any one stock, is made up to the stock holder.

15 In carrying out the invention, a stock certificate book or binder may be employed, which is illustrated in the accompanying drawings, in which—

Figure 1 represents the front page of said book, showing the guarantee certificate; Figs. 2 and 3, are examples of two of the stock certificates bound in the book, and Fig. 4 is a perspective view of the book disclosing the non-detachment notice.

20 An incorporated commercial company hereinafter termed the central company, is created, having the capital and facility of managing the manufacture and the marketing of a plurality of articles, which may belong to a variety of different classes. This central company, which is designated in Fig. 1, of the drawing as Smith, Adam & Smith, causes to be incorporated a plurality of separate and distinct sub-corporations, 25 hereinafter called the working companies, each of which is organized for exploiting one of said classes only. In place of incorporating said working companies, the central company may become interested in 30 working companies already formed as hereinafter specified. Separate stock certificates are issued for each of the working companies, two of such certificates being shown in Figs. 2 and 3 of the drawing, as issued by

35 the John Doe Company and the Jane Doe Company respectively. The stock certificates of each of the working companies, say ten, in which the central company is interested, are bound together in book form by a 40 wrapper as shown in Fig. 4. This wrapper contains a notice that the several certificates bound therein, cannot be detached and cannot be separately transferred without forfeiting the guarantee of the central company 45 hereinafter referred to.

The central company acquires in each of

the ten working companies a controlling amount of stock, say 51 per cent., places the same in trust with a trust company, the name of which is left blank in Fig. 1. The remainder of the stock is sold or acquired by various independent stock holders, each of whom purchases a book and will then come into possession of a like number of shares in each and every stock controlled by the central company and bound together as above described. The central company issues printed guarantees of the form shown in Fig. 1, one of such guarantees being incorporated in each of the books containing the stock certificates of the working companies. The guarantee discloses the name of the central company, the percentage of stock held by said company in all the working companies, the name of the trust company, and a statement to the effect that in the event of the average dividends paid on the shares inclosed falling below a stated percentage, the dividends of the stock held in trust by the central company will be applied to covering the deficiency of dividends on the stock certificates attached, provided none of the latter be removed.

45 The central company which should be equipped with the necessary capital, brain and labor, and other facilities, undertakes the management of the several working companies and the marketing of the various articles manufactured by said working companies and uses its best efforts to make the 50 same financially successful. Owing to this centralization of the various working companies, the various articles represented thereby may not only be manufactured at a reduced cost, but the channels used for 55 marketing some of these articles are available for marketing some or all of the other articles, so that in this way the distribution of the goods is greatly facilitated and cheapened.

60 When the dividends are declared by the several working companies corresponding payments are made to each of the stock holders. Should these payments when averaged, fall below the percentage mentioned in the "guarantee" and left blank in Fig. 1, then, the dividends accruing under the majority of the stock held in trust for the central company, are drawn upon and must be applied to make up the deficiency. 65 After the percentage mentioned in the "guarantee" has thus been made up and

paid over to the stock holders of the working companies from the stock of the central company, the remainder of the profit of the central company is distributed to the share 5 holders of said company. In this way the stock holders of the working companies are protected in a dual manner, first by averaging possibly inert stocks with active stocks, and secondly by their right to receive profits 10 from stock not held by them at all, but by the central company. At the same time the share holders of the central company are also in a position to earn a substantial profit by a careful selection of the working companies, an intelligent management of the central company and an economical distribution of the various articles handled.

The owner of each of the stock books, may of course detach and sell or otherwise dispose 20 of any one or more of the stock certificates bound therein. But in that event, not only the certificate so detached, but also all the certificates still remaining in the depleted book will lose the guarantee of the 25 central company, and shall be entitled only

to the profits actually earned by the working companies by which said certificates are respectively issued.

I claim:—

1. The combination in a composite stock certificate, of a dividend guarantee slip of a holding company, with a plurality of mutually united stock certificates of working companies, each of said certificates bearing a notice that upon a mutilation of the combination through the removal of one or more of said certificates, the dividend guarantee be vitiated.

2. A stock book containing a dividend guarantee sheet of a holding company, and a plurality of bound stock certificates of working companies, each of said certificates bearing a notice that upon the removal of one or more of said certificates from said book, the dividend guarantee be vitiated.

MOÏS H. AVRAM.
